UNITED STATES PATENT OFFICE.

FRITZ GERHARD AND LUDWIG ANWANDER, OF ZURICH, SWITZERLAND.

ICE-BOX.

SPECIFICATION forming part of Letters Patent No. 669,939, dated March 12, 1901.

Application filed February 13, 1900. Serial No. 5,117. (No model.)

To all whom it may concern:

Be it known that we, FRITZ GERHARD and LUDWIG ANWANDER, subjects of the Emperor of Germany, residing at Zurich, Switzerland, 5 have invented certain new and useful Improvements in Ice-Boxes; and we do hereby declare the following to be a full, clear, and exact description of the invention, such as will enable others skilled in the art to which it appertains to make and use the same.

The present invention relates to an improved ice-box for household and commercial purposes, which consists of a double-walled door, a double floor, and a double-walled 15 wooden box in which the ice-box is placed over the cooler. The double walls and the double floor form intermediate spaces, which are connected with each other, as well as with ice-box and cooler, so that when the ice-box is 20 closed the air may circulate through all the parts of the interior of the ice-box. By this arrangement a dry and low temperature is obtained in the ice-box and the sweating of the same is avoided. The circulation of the air 25 between the ice-box and the cooler, on the one hand, and the intermediate walls touching these parts, as well as the intermediate parts of the door and walls to which they are attached, is effected through openings in said 30 walls. To prevent the entrance and outlet of air when the door is opened, (between the cooler and the intermediate parts communicating with it,) the openings which effect the circulation of air are provided with valves 35 which when the door is opened close automatically and which when the door is closed open again. By this arrangement a great saving is effected.

The accompanying drawings illustrate the 40 invention.

Figure 1 is a vertical sectional view on a plane parallel with the doors when closed, looking to the front. Fig. 2 is a sectional view on a plane cutting through one of the doors. 45 Figs. 3 and 4 are detail sectional views on an enlarged scale.

Like letters of reference mark the same parts in all of the figures of the drawings.

The outer walls of the double-walled wooden 50 box *c* and the double-walled door *e*, as well as the outer wall of the ice-box, are covered on their inside with a thick layer of paint *p*

and are provided with a stout layer of cardboard *q*, which both layers serve as non-conducting material. The inner walls of the 55 wooden box *c* and the door *e* and the inner part of the floor are lined with sheet-zinc. To prevent leakage of water into the wall-spaces *f*, the openings *d* between said spaces and the ice-box *a* are provided with interior protective plates or guards *o*. The openings *g*, arranged between the intermediate parts *f* and the cooler, are closed when the door is opened by springs *i*, which press the valve-bodies *h* into their seats on the outer sides of the inner walls. When the door is closed, these valves are held open by the arms *k*. When the door is opened, the arms *k* retract from the valve-bodies *h* and the valves are closed by the springs *i*. The air circulation between 70 the intermediate spaces *f* and the door *e* of the walls *c* is effected by two opposing valves *r*, which cover each other when the doors are closed, which on the one hand are placed in the frame of the door and on the other side 75 are placed in the edges of the door meeting this frame. The seats of the valves, as well as the springs pressing against these valve-bodies, are situated in the intermediate parts *f*. To each valve-body a pins, reaching through 80 the valve-opening when the door is opened, is attached. The pins *s* of the valve-bodies in the frame are situated exactly opposite to the pins of the valves in the doors, so that when the door is closed the two opposing pins 85 will push against each other, when they will be pushed back on their respective valve-bodies, whereby the pressure of the opposing pins is relieved, so that the springs of the valve-bodies press them against their seats. 90

In the bottom of the box, near the back wall, is situated a clack-valve *l*, with a clack that is weighted by a prolongation *n*. When the door of the ice-box is closed, the valve *l* will open on account of the air-pressure arising 95 in the box, and part of the air heated by the opening of the door may escape. A plate *o'* is provided over the valve *l* to prevent a loss of goods.

Having now fully described the nature of 100 this invention, what we claim is—

1. The combination in a refrigerator provided with an ice-tank, a cooling-chamber below it, and surrounding hollow walls forming

an air-space and having openings into both tank and chamber, of a valve in the air-space normally closing the opening between the air-space and cooling-chamber, a hinged door, 5 and an arm projecting inward from the door in position to move and hold the valve away from its opening when the door is closed, substantially as described.

2. The combination in a refrigerator, of a double wall with air-space between and a double-walled door with interior air-space, the edge of the door and its seat in the double wall being provided with openings which register when the door is closed, of a valve in the

wall opening into the air-space, a valve in the 15 door edge opening into its air-space, stems on said valves in line with each other whose combined length exceeds the thickness of the walls through which they pass, and springs for normally holding the valves closed when the door 20 is open, substantially as described.

In testimony whereof we have affixed our signatures in presence of two witnesses.

FRITZ GERHARD.
LUDWIG ANWANDER.
